UNITED STATES PATENT OFFICE.

GEORGE EDSON GILBERT, OF TORONTO, ONTARIO, CANADA.

DETACHABLE HEEL.

1,237,893.

Specification of Letters Patent. Patented Aug. 21, 1917.

Application filed May 9, 1917. Serial No. 167,447.

To all whom it may concern:

Be it known that I, GEORGE E. GILBERT, a subject of the King of Great Britain, and a resident of Toronto, Ontario, Canada, 5 have invented a new and Improved Detachable Heel, of which the following is a full, clear, and exact description.

My invention relates to rubber heels attachable to leather heels or heel lifts in a 10 manner to be detachable or interchangeable.

The prime object of my invention is to improve heels of the type in question, in various particulars, whereby to insure such an interengagement between the rubber and 15 leather heel elements as to make it impossible for the rubber heel to become accidentally detached or displaced, while at the same time the rubber heel may be secured in position or removed with facility.

20 The nature of the invention and its advantages will clearly appear from the specific description following.

Reference is to be had to the accompanying drawings forming a part of this specification in which similar reference characters indicate corresponding parts in all the 25 views.

Figure 1 is a side elevation partly in section of a portion of a shoe having my improved heel thereon;

Fig. 2 is an inverted plan view of a portion of the shoe and the permanent heel portion;

Fig. 3 is a transverse vertical section on 35 the line 3—3, Fig. 1;

Fig. 4 is a perspective view of the rubber heel;

Fig. 5 is a partly sectional front elevation of said rubber heel;

Fig. 6 is a side elevation of the rubber heel.

My improved heel is adapted to be applied to any ordinary boot or shoe indicated by the letter A. In carrying out my invention the permanent heel 10 may be of any approved construction and material, there being indicated a top lift 12 and an under lift or second lift 11. In the permanent heel I produce a depression designated by 45 the numeral 13 and generally of keystone form with the broader end toward the front. The material of the permanent heel at the depression 13 at the rear end and a portion of the sides of the recess overlaps in 50 the form of flanges 14, whereby to give the recess an undercut form, except at the front

portion thereof, as indicated at 15. Moreover, it will be observed from Fig. 2 that the forward ends of the side flanges 14 present transverse shoulders 16, the purpose of 60 which will presently appear.

My improved rubber heel designated generally by the numeral 17 is made of a shape to conform to the described formation of the permanent heel 10, for which purpose a block 65 or projection 18 is produced thereon inward at all sides from the edges of the heel and generally of keystone shape. If desired, the projection 18 may be reinforced by transverse reinforcing elements 19. At the rear portion, the projection 18 is made T-shape 70 in transverse section, being undercut or channeled as at 20 across the rear end and extending along the sides thereof short of the front end, thereby producing a flange 75 21. The forward terminals of the channel or undercut 20 produces transverse shoulders 22 on the block 18 beneath the flange 21 and these shoulders, when the rubber heel 17 is secured in position, are disposed 80 opposite and in frictional engagement with the transverse shoulders 16 of the heel 10. The front of the depression 13 presents a transverse front wall 23 and the transverse front wall 24 of the projection 18 corresponds.

With the described formation of the heels 10 and 17, the latter is inserted by entering the rear end of the block 18 in the depression 13 at the front of the latter and forward of the side flanges 14, the heel 17 being bent and otherwise manipulated in a manner that will be obvious. To pass the flange 21 beneath the flanges 14, the said flange 21 is of slightly less thickness than the depth of the undercut 15 in the heel 10 in order that the said flange 21 will not bind or buckle in being moved into position. Also, the space between the side flanges 14 on any given transverse line is slightly less than the width of the shank 25 of the projection 18 at the T-shaped portion thereof on a corresponding line; the result is that the flanges 14 compress the rubber at the shank 25 giving a firm holding engagement between the rubber heel and the permanent heel in addition to the actual interengagement due to the channel 20 and flanges 14. When the flange 21 is fully entered in the undercut 15, the forward portion of the projection 18 is sprung into the depression 13 so that the opposed shoulders 16 and 22 positively pre- 100 105 110

vent displacement in the plane of the heel rearwardly while the opposed front walls 23, 24 perform a similar office for preventing displacement of the rubber heel in a forward direction. Thus, the rubber heel is secured without the employment of adventitious fastening means and positively held against displacement or detachment while it will be seen that said rubber heel may 10 be readily removed by prying its front end outwardly until the described entering steps are reversed.

Having thus described my invention I claim as new, and desire to secure by Letters Patent:

1. A boot or shoe heel comprising a permanent heel having a recess therein of general keystone form, and bordered at the four sides by the material of the said heel, said 20 material overlapping at the rear end and sides of the recess to give the latter an undercut form for a portion thereof, the forward ends of the overlapping side portions presenting transverse shoulders, and a detachable rubber heel having at the inner side thereof a locking projection of general keystone shape and positioned to be inward at all sides from the edges of the rubber heel, the rear portion of the said projection being 25 T-shaped in cross section presenting a flange at the sides and at the rear, the forward portion of the said projection presenting rear-

wardly facing, transverse shoulders at the forward end of the said shank opposing and in contact with the transverse shoulders of 35 the permanent heel.

2. A boot or shoe heel comprising a permanent heel having a recess therein of general keystone form, and bordered at the four sides by the material of the said heel, said 40 material overlapping at the rear end and sides of the recess to give the latter an undercut form for a portion thereof, the forward ends of the overlapping side portions presenting transverse shoulders; and a detachable rubber heel having at the inner side 45 thereof a locking projection of general keystone shape and positioned to be inward at all sides from the edges of the rubber heel, the rear portion of the said projection being 50 T-shaped in cross section presenting a flange at the sides and at the rear, the shank of the T at any transverse line drawn there-through being of slightly greater width than the space between the side flanges of the 55 permanent heel on a corresponding line, and the forward portion of the said projection presenting rearwardly facing transverse shoulders at the forward end of the said shank, the side portions of the flange of the 60 rubber heel being snugly slidably in the undercut portion of the recess.

GEORGE EDSON GILBERT.
